UNITED STATES PATENT OFFICE.

AUGUST ALEXANDER LUNDEEN, OF LYNBROOK, NEW YORK.

JAR CAP.

Application filed June 9, 1927. Serial No. 197,677.

This invention relates to closure caps or covers for jars or other similar containers, the same being especially designed for use in connection with containers such as mustard jars, in which the contents is usually served by a small serving implement, such as a paddle or spoon.

In jars or containers of this character especially those used in restaurants, it has been noticed that the contents hardens and adheres to the necks and covers, presenting an unsightly and unsanitary condition.

It is therefore the principal object of the present invention to provide an improved closure cap which is detachably associated with the neck of the jar or container so that the same may be readily removed therefrom, cleansed, sterilized and replaced at frequent intervals.

The invention furthermore comprehends a closure cap which is provided with means for effectually covering the notch through which the handle of the serving implement projects.

Other objects reside in the features of simplicity of construction, economy of production and the general efficiency derived therefrom.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a perspective view of a closure cap constructed in accordance with the invention applied to a jar, illustrating the same in closed condition with the notch open;

Fig. 2 is a perspective view of the cap removed from the jar and illustrating the notch in closed condition;

Fig. 3 is a vertical fragmentary sectional view through the jar with the closure cap plate in closed condition.

Referring to the drawings by characters of reference, the cap includes an annular body 10 provided with inner and outer depending marginal flanges 11 and 12, which body is adapted to embracingly engage the upper open end or neck A of the jar or container B. The body as constructed defines a central

opening 13 through which access may be had to the interior of the jar or container. As usually constructed, the neck A is formed with a bead or beads C and coacting lugs 14 formed on the outer depending flange 11 for detachably connecting the cap body 10 to the neck. The cap further includes a cover member 15 which is hingedly connected at 16 to the body 10 and is swingable respectively to closed or open positions as illustrated in Figs. 1 and 2. The cover member is formed with a radial notch 17 and is provided with a radially projecting lip 18 which protrudes beyond the outer periphery of the cap body 10 to facilitate the opening of the cover member. A disk-like closure element 19 is mounted for turning movement on the cover member 15 by means of a rivet or other attaching device 20, and said disk-like element 19 is formed with a corresponding radial notch 21 in its periphery.

In practice, the cap may be employed to completely close and protect the contents by turning the disk-like element 19 so that its notch 21 is disposed out of registry with the notch 17 of the cover member 15. When it is desired to use a serving implement, the notches may be registered as illustrated in Fig. 1, to allow the handle to project upwardly through said aligned notches. In serving the contents, the cover member 15 is swung to the open position as illustrated in Fig. 2, allowing the contents to be dispensed through the central opening 13 defined in the cap body.

When it is desired to cleanse and sterilize the cap and jar, the cap structure may be readily removed by disengaging the lugs 14 from the bead or beads C. It will be noted that the inner flange 12 projects downwardly a sufficient distance into the neck to prevent the contents from clogging in the neck so that waste of the same is obviated.

What is claimed is:

1. A cap for containers of the character set forth, including a neck embracing body detachably connected therewith and having an opening therethrough, a cover hingedly connected to said body for swinging movements to open and closed positions respectively, said cover having a notch and a rotary element on said cover having a notch for registry with the cover notch to permit the handle of a serving element to project therethrough, said rotary element being shiftable to a position to dispose its notch out of regis-

try with the cover notch whereby to completely close the container.

2. As a new article of manufacture, a cap for containers of the character set forth, 5 comprising an annular body having inner and outer marginal depending flanges, the outer flange having means adapted to coact with the neck of the container to detachably associate the same therewith, the inner flange 10 defining a dispensing opening, a hingedly connected cover member on the cap body, having a radial notch, and a rotary element having a notch mounted on the cover member for turning movement to dispose the 15 notch respectively in and out of registry with the cover notch.

3. As a new article of manufacture, a jar cap comprising an annular body of substantially inverted U-shaped cross-sectional configuration adapted to embracingly engage 20 over the neck of a jar, a cover member hingedly connected thereto for swinging movements to open and closed positions, said cover member having a radial notch in one of its edges, and a disk-like closure member rotatably mounted on the cover, having a complementary radial notch in one of its edges respectively movable to registering and non-registering positions of the notches, as and for the purpose specified. 25

AUGUST ALEXANDER LUNDEEN.
